N.Y., assignors to Motiva Ltd., Jamaica Estates, N.Y.,
a corporation of New York

Filed June 30, 1966, Ser. No. 2,877

Term of patent 14 years

(Cl. D61—1)

FIG. 1 is a front and side perspective view of a rear projection viewer or similar article, showing our new design;

FIG. 2 is a top plan view;

FIG. 3 is a rear and side perspective view;

FIG. 4 is a bottom and rear perspective view;

FIG. 5 is a side elevational view thereof, the opposite side being substantially a mirror image thereof, and

FIG. 6 is a fragmentary cross-sectional view taken in the plane of line 6—6 in FIG. 1 to show the rim of the frame of the screen on the viewer.

A portion of FIG. 1 is diagonally lined to indicate the translucency of the screen of the viewer.

We claim:

The ornamental design for a rear projecting viewer of similar article, as shown and described.
